WALL FIXTURE FOR DEODORIZING LAMPS

Charles W. Flood, Jr., East Orange, N. J., assignor
to Westinghouse Electric Corporation, East
Pittsburgh, Pa., a corporation of Pennsylvania

Application May 9, 1952, Serial No. 19,647

Term of patent 14 years

(Cl. D48—4)

To all whom it may concern:

Be it known that I, Charles W. Flood, Jr., a citizen of the United States, residing at East Orange, in the county of Essex and State of New Jersey, have invented a new, original, and ornamental Design for a Wall Fixture for Deodorizing Lamps, of which the following is a specification, reference being had to the accompanying drawing, forming a part hereof.

Fig. 1 is a front perspective view of a wall fixture for deodorizing lamps showing my new design;

Fig. 2 is a top plan view thereof;

Fig. 3 is a side elevational view thereof, partly broken away in section; and

Fig. 4 is a bottom plan view.

I claim:

The ornamental design for a wall fixture for deodorizing lamps, as shown.

CHARLES W. FLOOD, JR.
